UNITED STATES PATENT OFFICE

EDWIN GEBHARDT, OF CINCINNATI, OHIO.

DESIGN FOR A LAPEL-BUTTON.

No. 37,899.

Specification for Design.

Patented March 20, 1906.

Application filed January 26, 1906. Serial No. 298,072. Term of patent 3½ years.

To all whom it may concern:

Be it known that I, EDWIN GEBHARDT, a citizen of the United States, residing in Cincinnati, county of Hamilton, and State of Ohio, have invented a new, original, and ornamental Design for Lapel-Buttons, reference being had to the accompanying drawing, forming part hereof, in which the figure is a plan elevation of the lapel-button, showing my design.

I claim—
The ornamental design for a lapel-button, as shown.

EDWIN GEBHARDT.

Witnesses:

EDW. C. NATLOCK,
GLENA PRITCHARD.
